US00D789765S

(12) **United States Design Patent** (10) **Patent No.:** **US D789,765 S**
Wang (45) **Date of Patent:** **** Jun. 20, 2017**

(54) **HANDLE**

(71) Applicant: **TAIWAN FU HSING INDUSTRIAL CO., LTD.**, Kaohsiung (TW)

(72) Inventor: **Chi-Fu Wang**, Kaohsiung (TW)

(73) Assignee: **TAIWAN FU HSING INDUSTRIAL CO., LTD.**, Kaohsiung (TW)

(**) Term: **15 Years**

(21) Appl. No.: **29/551,821**

(22) Filed: **Jan. 17, 2016**

(30) **Foreign Application Priority Data**

Dec. 21, 2015 (TW) 104307113

(51) **LOC (10) CI.** **08-06**

(52) **U.S. Cl.**

USPC **D8/308**

(57) **CLAIM**

The ornamental design for a handle, as shown and described.

DESCRIPTION

FIG. 1 is a perspective view of a handle showing my new design;
FIG. 2 is a front view thereof;
FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines represent the unclaimed opening and inside portion of the base of the handle and form no part of the claimed design.

1 Claim, 7 Drawing Sheets
